UNITED STATES PATENT OFFICE.

GILMAN W. BROWN, OF WEST NEWBURY, MASSACHUSETTS, ASSIGNOR OF
ONE-HALF TO HAYDEN BROWN, OF SAME PLACE.

AUTOMATIC FIRE-ALARM SYSTEM.

SPECIFICATION forming part of Letters Patent No. 463,608, dated November 17, 1891.

Application filed August 21, 1891. Serial No. 403,377. (No model.)

To all whom it may concern:

Be it known that I, GILMAN W. BROWN, of West Newbury, in the county of Essex and State of Massachusetts, have invented certain new and useful Improvements in Automatic Fire-Alarm Systems, of which the following is a specification.

This invention in automatic fire-alarm systems has for its object to provide a novel system, as will be described, whereby the sounding of false alarms is obviated and the system rendered more reliable in case of fire.

In accordance with my invention one or more thermostats constructed as will be described and located in a building or structure to be protected are included in a normally-closed circuit supplied with current from a battery or other suitable source of electricity, and provided at a main or central station with a receiving-instrument consisting, essentially, of an audible signal controlled by the polarized armature of an electro-magnet. The thermostat referred to is constructed, as will be described, so as to produce reversals of the current over the main line and thereby operate the electro-magnet to sound the audible signal in case of a fire. The receiving-instrument, preferably, also comprises a visual indicating-instrument by which the condition of the line-circuit may be made known to the operator or attendant at the fire-station or central office. The polarized armature of the electro-magnet is preferably adjusted so as to be withdrawn from its electro-magnet when the strength of the current flowing over the line falls below the normal—as, for instance, in case of a weakening of the battery, a short-circuiting of the line, or a dead break in the line, the withdrawal of the armature operating the audible signal to call the attention of the operator at the central office to the fact that a change in the condition of the main line has taken place. The visual indicating device referred to is preferably provided with a scale suitably marked to indicate a weakening of the battery, a broken line, or a fire, whereby the attendant upon hearing the alarm may see at a glance under what condition the line-circuit is placed.

The particular features of my invention

will be pointed out in the claims at the end of this specification.

Figure 1 is an elevation of the receiving-instrument employed on an automatic fire-alarm system embodying my invention. Fig. 2 is a sectional detail, on an enlarged scale, of the upper portion of the receiving-instrument, the section being taken on the line 2 2; Fig. 3, a top or plan view of a thermostat embodying my invention, the thermostat being shown in operative condition; Fig. 4, a longitudinal section of the thermostat shown in Fig. 3 on line 4 4; Fig. 5, an under side view of the thermostat shown in Fig. 3; Fig. 6, a longitudinal section of the thermostat, shown in Fig. 3 on line 4 4, showing the thermostat as having been operated. Fig. 7 is a diagram of circuits showing two thermostats as connected to the receiving-instrument, only a portion of the case of which is shown, the thermostats being in their operative positions ready to send in an alarm of fire; and Fig. 8, a diagram of circuits, showing the thermostats connected to the operative parts of the receiving-instrument, the thermostats being shown as having been operated by a fire.

The receiving-instrument of my improved automatic fire-alarm system consists, essentially, of an audible signal, (shown as an electro-mechanically-operated gong or bell,) of any usual or well-known construction, it consisting of a striker or an arm a , secured to a shaft a' , having the crank-arm a^2 , joined by a connecting-rod a^3 to a pivoted arm a^4 , provided with a detent a^5 , co-operating with a detent on a lever or arm a^6 , having at its upper end a detent a^7 , (shown in dotted lines in Fig. 1,) with which co-operates a detent a^8 on an armature-carrying lever a^9 , pivoted as at a^{10} , and provided with an armature a^{12} for an electro-magnet a^{13} , suitably supported within the case a^{14} of the receiving-instrument. The pivoted arm a^4 is rotated in the usual manner, as herein shown, by a system of gears or clock-work a^{15} , actuated by a normally-wound-up spring a^{16} , or it may be a weight. The armature a^{12} of the electro-magnet is preferably composed of hardened steel and polarized or made a permanent magnet, and under normal conditions the polarity of the electro-magnet a^{13} is such as to attract the armature

a^{12} and place the detent a^8 on the armature-lever a^9 in the path of movement of the detent a^7 on the arm a^6 , and thereby prevent the movement of the pivoted arm a^4 , and consequently hold the striker on the arm a away from the gong or bell A.

In accordance with my invention, the polarized armature a^{12} of the electro-magnet is repelled away from the poles of the magnet a^{13} by a reversal in the current flowing over the line in which the electro-magnet a^{13} is located. The reversal of the current is effected by means of a pole-changing thermostat, preferably constructed as shown in Figs. 3 to 15, inclusive. The thermostat consists, essentially, of a block or supporting-base b of insulating material—usually wood, porcelain, or hard rubber—and provided on one face with two springs $b' b^2$, (shown as flat strips of metal,) constituting the other set of pole-changing arms for the thermostat. These springs are firmly secured to the base b at one end, they being herein shown as bent down over the rear side of the block b , and the said 20 strips have secured to them binding-screws $b^3 b^4$, respectively, to which the line-wires are secured, as will be described. The free ends of the strips $b' b^2$ are normally secured by a fusible material or solder—such as an alloy 25 of lead, tin, cadmium, &c.—to conducting-strips $b^5 b^6$. (Shown in Figs. 3 to 6, inclusive, as secured to the front side of the block or supporting-base b .) The conducting-strips $b^5 b^6$, as herein shown, have secured to them binding-screws $b^7 b^8$, by which the line-wires may 30 be connected with the thermostat. The spring-strips $b' b^2$ have secured to them on their under side projecting pole-changing arms $b^9 b^{10}$, one of which is shown in full lines, Figs. 4 to 6, and both of which are indicated by dotted lines in Fig. 5. The pole-changing arms $b^9 b^{10}$ project into a recess or cavity b^{12} in the base b and co-operate with the circuit-terminal, herein shown as rods or bars $b^{13} b^{14}$, 45 extending across the said recesses. The circuit-terminal b^{13} is connected by a conducting-wire b^{15} to the binding-screw b^8 , and the circuit-terminal b^{14} is connected by conducting-wire b^{16} to the binding-screw b^7 , as clearly 50 shown in Fig. 5. The pole-changing arms $b^9 b^{10}$, as herein shown, are provided with fingers, which extend under the circuit-terminals $b^{13} b^{14}$ when the thermostatic springs $b' b^2$ are in their normal condition, (shown in 55 Figs. 3 and 4,) but which are adapted to be brought up into contact with the circuit-terminals $b^{13} b^{14}$ when the thermostatic springs are released by the melting of the solder or fusible connection, as in the case of a fire.

This position of the thermostatic springs is 60 indicated in Fig. 6. In the normal condition of the system the thermostatic springs $b' b^2$ are secured to the contact-strips $b^5 b^6$ by the fusible connection, and the armature a^{12} is attracted by its magnet a^{13} , the current flowing over the line in what may be termed the "normal" direction, as indicated by the ar-

row 20 in Fig. 7. If now the thermostat should be operated, as by the breaking out of a fire in its vicinity, the thermostatic springs $b' b^2$, being released by the melting of a fusible connection, would fly upward and thus bring the pole-changing arms $b^9 b^{10}$ into contact with the circuit-terminals $b^{13} b^{14}$, in which case the current would flow over the line, as indicated in Fig. 8, it passing from the positive pole of the battery B in the direction indicated by arrow 20 until it came to the spring b^2 , and the connection between the spring b^2 and its co-operating strip b^6 being interrupted, 75 the current will flow down the pole-changing arm, as indicated by arrow 21, and by the circuit-terminal b^{14} and wire b^{16} to the binding-screw b^7 , from whence it would pass into the receiving-instrument, and through the 80 electro-magnet a^{13} in a reverse direction, and thence out over the line again to the binding-screw b^8 , from whence it would pass by the conducting-wire b^{15} and terminal b^{13} to the pole-changing arm b^9 , and thence by the spring b' 85 to the negative pole of the battery. By the reversal of the current over the main line, as thus described, the polarized armature a^{12} is repelled by its magnet a^{13} and the armature-lever a^9 is turned on its pivot a^{10} , so as to withdraw the detent a^8 from engagement with the 90 detent a^7 on the lever a^6 , and thereby permit the spring or motor a^{16} to turn the pivoted arm a^4 and the striker-arm a and sound the gong or bell A, thus giving an alarm at the 95 receiving-instrument that a change in the condition of the circuit has been effected.

In order that the operator at the central office may positively know whether the alarm thus sounded is due to the operation of the 100 thermostat or to a broken wire or for other cause, an indicating device, preferably visual, is employed, which may be and preferably is located within the case a^{14} . The indicating device, as herein shown, consists of a galvanometer-coil c , having pivotally suspended within it a polarized needle c' , preferably of hardened steel, mounted on a shaft or arbor c^2 within the coil c , said arbor having secured to it a pointer c^3 , which co-operates with the 110 plate or dial c^4 , secured in a suitable manner to the frame-work of the case. The dial c^4 , as herein shown, (see Fig. 1,) is provided with four graduations or indications marked, respectively, "OK," "battery run down," "line 115 broken," and "fire," the line-broken indication occupying a central or zero position on the scale. If the galvanometer-coil is not being traversed by an electric current, the pointer c^3 would stand on the zero position or 120 line-broken indication, and when the current is traversing the coil in its normal direction the pointer c^3 will be turned to one side of the zero position—as, for instance, to the left, as shown in Fig. 1—and when the current is 125 reversed, as has been described, the pointer will be deflected to the indication marked "fire." The attendant at the main office by glancing at the dial might ascertain from the

pointer the fact that the battery had been weakened; but in order to render this feature more positive I prefer that the alarm or audible signal *a* should also be sounded when the 5 battery is thus weakened. This may be accomplished by adjusting the tension of the retractor for the armature *a*¹², which retractor is herein shown as a spiral spring *d'*. When the battery has been weakened, the spring *d'* o will withdraw the armature *a*¹² from its electro-magnet and release the motor mechanism and sound the alarm *A*. In case of a broken wire the current will cease flowing over the main line and the pointer *c*³ will fall to zero or to the indication marked "broken line." So, also, if the main line should be short-circuited the same effect would be accomplished, and in either case the armature *a*¹² would be withdrawn by its spring *d'* to start the motor and operate the alarm. In the normal condition of the main line the pointer *c*³ stands at the indication "OK;" but when the thermostat is operated, as by the breaking out of a fire, the current is reversed and the pointer *c*³ will 5 pass beyond the zero position to the other side toward the indication marked "fire." In this way the operator at the fire or receiving station is enabled to know positively for what cause the alarm has been sounded; or, in other 30 words, the true condition of the line-circuit at all times is made known to him, so that in case of any accidents of the line-circuit the same may be readily repaired without rendering the circuit inoperative for any considerable length of time.

Referring now to Figs. 7 and 8, the current in the normal condition of the circuit, as indicated in Fig. 8 by arrow 20, passes through the galvanometer and electro-magnet back 40 over the line-wires, whereas when the thermostat is operated and the polarity reversed the current passes through the electro-magnet and galvanometer back over the line.

In practice it might happen that the current 45 would be reversed by the operation of one thermostat, the alarm sounded, and the pointer *c*³ deflected to the indication marked "fire," and immediately after a second thermostat might be operated and the current again reversed and the current restored to its normal direction, thus restoring the parts of the receiving-instrument to their normal condition.

In order that the operator may know positively whether the alarm is due to a fire, I 55 have provided a detent or catch *e* (see Figs. 1 and 2) for the pointer *c*³, the said detent or catch being located near the "fire" indication and adapted to engage the pointer *c*³ when the latter has been moved to the "fire" indication by the reversal of the current. So, also, 60 I prefer that the polarized armature should be withdrawn by its spring *d'* when repelled from its magnet sufficiently far to remove it from the influence of its magnet, thus requiring that the said armature be replaced in operative position by the operator.

I claim—

1. In an automatic fire-alarm system, the combination, with a main-line circuit, an electro-magnet located therein and provided with 70 a polarized armature, and a receiving-instrument controlled in its operation by the said polarized armature, of a pole-changing thermostat located in the main-line circuit and consisting of two sets of pole-changing arms, one 75 set being normally connected in the main line by a fusible connection and the other set being normally not included in the said circuit, but adapted to be included in the said circuit by the melting of the fusible connection to 80 re-establish the main line with reversed polarity after the said line has been opened by the operation of the fusible connection, substantially as described.

2. In an automatic fire-alarm system, the 85 combination, with a main-line circuit, an electro-magnet located therein and provided with a polarized armature, and an audible signal controlled in its operation by the said polarized armature, of a pole-changing thermostat 90 located in the main-line circuit and consisting of two sets of pole-changing arms, one set being normally connected in the main line by a fusible connection and the other set being normally not included in the said circuit, 95 but adapted to be included in the said circuit by the melting of the fusible connection to re-establish the main line with reversed polarity after the said line has been opened by the operation of the fusible connection, substantially as described.

3. In an automatic fire-alarm system, the combination of the following instrumentalities, viz: a main-line circuit, an electro-magnet located in said circuit and provided with 105 a polarized armature, a visual indicating device included in the main-line circuit, and a pole-changing thermostat adapted to be operated by increase in temperature to reverse the polarity of the main line and operate the visual indicator reversely, substantially as described.

4. In an automatic fire-alarm system, the combination of the following instrumentalities, viz: a main-line circuit, an electro-magnet 115 located therein, an audible signal controlled by the said electro-magnet, a visual indicating device operated by changes in condition of the circuit, and a pole-changing thermostat, substantially as described.

5. A pole-changing thermostat having two sets of pole-changing arms, one set consisting of conducting-springs held in tension by fusible solder and in position to conduct the current in one direction, the other set of pole-changing arms being connected to the said springs and normally not included in the line-circuit, but which are included therein by the operation of the said springs to reverse the line-current when said springs are released, 125 substantially as described.

6. The herein-described pole-changing thermostat, consisting of a base, conducting-springs secured thereto at one end and pro-

vided with pole-changing arms, conductors on said base, fusible connections joining the said conducting-springs to the said conductors, and circuit-terminals with which the pole-changing arms co-operate when the said springs are released by the melting of the fusible connections to re-establish the said circuit and reverse the polarity of the same, substantially as described.

In testimony whereof I have signed my name to this specification, in the presence of two subscribing witnesses, this 8th day of August, A. D. 1891.

GILMAN W. BROWN.
